INVENTOR,

Robert L. Shaw,

BY Gardner & Stewart, ATTY'S.

UNITED STATES PATENT OFFICE.

ROBERT L. SHAW, OF PATERSON, NEW JERSEY.

JACQUARD-CARD WIRE.

SPECIFICATION forming part of Letters Patent No. 658,870, dated October 2, 1900.

Application filed January 18, 1900. Serial No. 1,841. (No model.)

To all whom it may concern:

Be it known that I, ROBERT L. SHAW, a citizen of the United States, residing in Paterson, in the county of Passaic and State of New Jersey, have invented certain new and useful Improvements in Jacquard-Card Wires; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

15 My invention relates to jacquard-card wires; and the object of my invention is to provide a wire of this nature which shall comprise in itself means for detachably securing it in position on the lacings of and between 20 the pattern-cards, thus doing away with tying-strings or other separate means for securing said wire in position.

25 My invention consists in the improved card-wire and in the combination of several of the same with the interlaced pattern-cards.

Referring to the accompanying drawings, in which like letters of reference indicate corresponding parts in each of the several figures, Figure 1 is a perspective view of my 30 improved card-wire in position between the pattern-cards and on the connecting-lacings therefor. Fig. 2 is an enlarged perspective view showing in detail portions of two adjoining pattern-cards, their connecting-lacings, 35 and the wire between them and connected to said lacings. Fig. 3 is a detail view of a portion of the card-wire, showing its securing means; and Fig. 4 is a vertical sectional view taken on the line $x-x$ of Fig. 2.

40 In said drawings, a indicates the pattern-cards, provided, as usual, with perforations b , near the ends thereof and at any other desired points therein, through which extend the lacings c , which interconnect said pattern-cards, crossing each other between said 45 cards.

50 d indicates card-wires, one situated between every two pattern-cards and having its ends projecting beyond the edges of said cards in the usual manner.

The wires d are provided at their points of

junction with the lacings of said pattern-cards with preferably elongated loops e , the entrance f of each of which is somewhat contracted. Said loops are adapted to receive 55 the lacings connecting the members of each pair of pattern-cards. If desired, there may be one loop corresponding to each lacing, though it may be found sufficient to provide the wires with only those loops which are situated near their ends and which receive the outermost lacings. The loops may be of any 60 desired form, provided the entrance of each of them is so contracted that when the lacing is once received it cannot be easily detached 65 from said lacings. That form of loop which I have shown in Fig. 3, which incloses a triangular recess, is perhaps preferable, because it is as simple as any form of loop that could be devised and affords very little play to and 70 acts to snugly hold in place the lacings when they have been received by it. At the same time by virtue of its triangular shape the recess facilitates the detachment of the cards from the wire when this is effected manually. 75

It is obvious that if the loops are each made of a size which shall as much as possible conform to the size of the lacing which said loops shall contain there will be little, if any, play 80 between the wires and the lacings.

By forming the wire of elastic material, should the entrance f to each loop be contracted less than the thickness of the lacings, the insertion of the lacings into the loop will be facilitated, for then the entrance to the latter 85 can be readily widened by slightly bending the wire at the loop portion thereof, and the wire upon being released will of itself assume its former essentially-straight shape.

Having thus fully described my invention, 90 what I claim as new, and desire to secure by Letters Patent, is:

1. A jacquard-card wire provided with a plurality of loops therein adapted to receive the corresponding card-lacings, each loop having a contracted entrance and being elastic, 95 substantially as described.

2. A jacquard-card wire bent to form a plurality of loops therein adapted to receive and closely embrace the corresponding card-lacings, each loop having a contracted entrance and being elastic, 100 substantially as described.

3. A jacquard wire bent to form a plurality of loops therein adapted to receive and closely embrace the corresponding card-lacings, each loop being elastic and being normally substantially closed, and said loop being adapted to be opened by bending it against the force of its elasticity, substantially as described.

In testimony that I claim the foregoing I have hereunto set my hand this 15th day of 10 January, 1900.

ROBERT L. SHAW.

Witnesses:
